UNITED STATES PATENT OFFICE.

MARTIN KENNEDY, OF HEGEWISCH, ASSIGNOR TO THE UNITED STATES ROLLING STOCK COMPANY, OF CHICAGO, ILLINOIS.

MODE OF MAKING TURN-BUCKLES.

SPECIFICATION forming part of Letters Patent No. 395,281, dated December 25, 1888.

Application filed October 17, 1888. Serial No. 288,399. (No model.)

To all whom it may concern:

Be it known that I, MARTIN KENNEDY, a citizen of the United States, residing at Hegewisch, in the county of Cook and State of Illinois, have invented a certain new and useful Improvement in Turn-Buckles, which is fully set forth in the following specification, reference being had to the accompanying drawings, in which—

10 Figure 1 is a view of one of the bars which I employ in carrying out my process, the same being shown in its straight condition before the first heating and bending; Fig. 2, a similar view showing the bar after the ends have 15 been heated and bent; Fig. 3, an edge view of the bar shown in Fig. 2; Fig. 4, a view showing the turn-buckle in an unfinished state, one end being finished and the other ready for the final heating and swaging; Fig. 20 5, a view of the finished turn-buckle; Fig. 6, a sectional view of the same, taken on the line 1 1 of Fig. 5; and Fig. 7, an end view of the unfinished end shown in Fig. 4.

Like letters refer to like parts in all the figures of the drawings.

My invention relates to the manufacture of turn-buckles, and has for its object to simplify and consequently cheapen the construction of these articles.

30 To these ends my invention consists in certain novel features, which I will now proceed to describe, and will then particularly point out in the claims.

In the manufacture of turn-buckles as now 35 ordinarily conducted it is customary to take two flat iron bars and weld their ends to intermediate plugs placed between said ends and forming the body of the end of the turn-buckle. This makes a solid end at each end 40 of the turn-buckle, and after reheating a hole is punched through each solid end by means of a powerful apparatus for this purpose. It will be seen that a large amount of waste metal is thus employed in the process of manufacturing now in use, and that a very 45 powerful apparatus is necessary. Moreover, the proper heating of the various parts requires a great deal of time and fuel. It is to obviate these disadvantages that I have devised my present improved method, which is 50 carried out in the following manner:

For the construction of each turn-buckle two flat bars, A, having the form shown in Fig. 1, are employed, said bars having a length somewhat greater than the length of the finished turn-buckle. These bars are first heated 55 at their ends, and the ends, when thus heated, are swaged or bent into the form shown in Figs. 2 and 3 of the drawings by dies or other suitable means. It will be observed that not 60 only are the ends of the bars bent downward or offset, as shown at a, but this offset portion is also given a transverse curvature, as shown more particularly in Fig. 7. Two of the bars having the form shown in Figs. 2 and 3 are 65 placed together and then heated at one end. It will be observed that the curvature of the offset ends leaves a space, a', between the ends, so that the ends may be readily and quickly heated, the heat having access to both 70 sides of the bars. When sufficiently heated, the ends of the two bars are placed in a suitable die, and a punch is introduced and forced down between them through the opening a'. This punch, in conjunction with the die, gives 75 to the ends of the bars the form shown at the left end of Fig. 4 and at both ends of Figs. 5 and 6. The ends of the two bars are thoroughly welded together, and at the same time the opening a' assumes the circular form 80 shown in Fig. 6. The other ends of the bars are then similarly heated, placed in the die, and punched, thus completing the turn-buckle, which, when finished, has the form shown in Figs. 5 and 6.

85 It will be observed that all superfluous metal is entirely done away with in the method of construction just described. The plugs heretofore employed to form the ends or heads of the turn-buckle are entirely dispensed with, 90 and only the metal originally in the bars is used. Moreover, the punch, instead of passing through a solid mass of metal to form the holes in the ends or heads, simply passes through and enlarges the opening a' between 95 the bent ends of the bars. Compared with the ordinary process, there is comparatively a small amount of metal to be heated, and that small amount can be heated much more thoroughly and quickly, owing to the fact that 100 the heat has access to all parts of the metal to be heated. The process consumes a smaller

amount of time, there being less parts to handle, and they being more readily manipulated, heated, and punched. Owing to these advantages I am enabled to produce a much cheaper article without in any way sacrificing its quality.

It is obvious that various modifications in the details of construction and arrangement of the parts may be made without departing from the principle of my invention, and I therefore do not wish to be understood as limiting myself strictly to the precise details hereinbefore described, and shown in the drawings.

Having thus described my invention, what I claim as new, and desire to secure by Letters Patent, is—

1. The improvement in the art of manufac-

turing turn-buckles, which consists in first offsetting the ends of two flat bars and imparting to the said ends a transverse curvature and then welding together and shaping said ends, substantially as and for the purposes specified.

2. The improvement in the art of manufacturing turn-buckles, which consists in first offsetting and imparting a transverse curvature to the ends of two flat bars and then welding and shaping said ends by placing them in a suitable die and forcing a plunger into the opening between them, substantially as and for the purposes specified.

MARTIN KENNEDY.
